UNITED STATES PATENT OFFICE

2,478,569

STEAM GENERATOR

Harry Peter Cooper, Chicago, Ill.

Application March 8, 1945, Serial No. 581,641

3 Claims. (Cl. 122—37)

1 My invention relates to steam generators for steam pressing irons and particularly to means for supplying relatively dry steam to a combination steam and electric iron such as is shown in my Patent No. 2,025,092 on Pressing iron, patented December 24, 1935.

It is a purpose of my invention to provide a constant source of steam, the dryness of which remains substantially constant, and which requires no return system for circulating steam such as is commonly used in steam supply combinations for pressing irons.

My invention produces steam that is of such dryness that whatever liquid may be formed by condensation of the steam is formed within the iron and is distributed through the iron. My improved steam generating device is particularly applicable to that type of pressing iron which uses an electric heating means in conjunction with the steam and from which steam is discharged at a desired point or points while the iron is in use. In such an iron, it is desirable to have steam of a constant quality of dryness.

My improved steam generator, in combination with a regulator to hold the pressure of the steam below the water pressure of the supply line and to maintain the water supply in the boiler at substantially a constant level, is particularly capable of producing such dry steam of constant quality.

It is a further purpose of my invention to provide a compact steam generator of relatively large capacity so that one of said generating units can supply more than one pressing iron with steam, should this be found to be necessary in an emergency.

In order to produce such dry steam as is desired in an iron of the character referred to, I have provided a steam generator that comprises stacked chambers, the lowermost one of which is a steam generating chamber, and the uppermost one of which is a dry steam and condensate removing chamber, and the intermediate chamber of which comprises a water and condensate receiving chamber.

I have provided a very simple structure that is highly reliable for this purpose, which is made up of tubular members that are secured together by means of nipples which also serve as means for establishing communication between the adjacent chambers and also as means for mounting a conduit for carrying the generated steam directly from the generating chamber to the upper steam collecting chamber. The means establishing communication between the adjacent cham-

bers provides for constant communication between the steam generating chamber and the water chamber above the same so that the water level in the water receiving chamber will be the water level of the boiler and provides means for returning the condensate collecting in the bottom of the steam collecting chamber to the main body of water in the water chamber below the same.

10 It is a further purpose of my invention to provide a steam generator of the above mentioned character in which the means for maintaining the constant communication between the adjacent chambers is spaced longitudinally from the means for establishing communication between the steam generating chamber and the steam collecting chamber, and to provide means between the outlet end of the conduit providing such communication between the steam generating chamber and the steam collecting chamber to prevent direct passage of steam from the outlet end of the conduit to a dry steam outlet provided in the top of the uppermost chamber of the generator.

25 It is another purpose of my invention to provide a steam generator that is simple and cheap in construction, being made up of a stack of tubular members with their longitudinal axes extending substantially horizontally connected together by the above referred to nipples and having closed end walls, which are provided with suitable openings for the mounting of the heating means provided in the generating chamber, pressure controlled means for controlling the operation of the heating means so as to maintain a maximum pressure of the dry steam below the water pressure from the water supply, and to provide a water inlet connection and other suitable connections between said generator and the water 30 level controlling means to maintain a constant level of water at a predetermined point in the intermediate tubular chamber. My invention also includes a novel mounting for the generator comprising a supporting member that includes 35 a connection leading to a drain valve and electrical heating means for the water in the generating chamber that is so constructed that the highest heat is obtained immediately below the inlet to the conduit that carries the steam generated in the generating chamber to the steam 40 collecting chamber.

45 Other objects and advantages of my invention will appear as the description of the drawings proceeds. I desire to have it understood, however, that I do not intend to limit myself to the 50 55

particular details shown or described, except as defined in the claims.

In the drawings—

Fig. 1 is a view partly in elevation and partly in vertical section of my improved steam generator and its mounting including the controlling means for the water level and the steam pressure;

Fig. 2 is a view partly in elevation and partly in vertical section of the water level controlling means used in conjunction with my steam generator; and

Fig. 3 is a view taken substantially on the line 3—3 of Fig. 1.

Referring in detail to the drawings, my improved steam generator is provided with a base 10 of any desired character from which a tubular column 11 extends, which is threaded to receive a solid plug 12 on which a T 13 is mounted, which has a nipple 14 connected therewith that is threaded into a nipple 15 extending through the tubular wall 16 of the bottommost chamber 17 of said steam generator so as to be fixed therein, in liquid-tight relation to said tubular wall. Said tubular wall has end walls 18 secured thereto in liquid-tight relation to thus provide the steam generating chamber 17.

Mounted on the tubular member 16 is the tubular wall 19 of the intermediate chamber, which is also provided with end walls 21 that are fixed thereto in liquid-tight relation. Nipples 22 and 23 are fixed in openings in the tubular walls 16 and 19 in liquid-tight relation thereto and serve as means for connecting said tubular members 16 and 19 to each other in fixed relation. The nipple 22 also serves as means to establish constant communication between the chamber 17 and the chamber 20.

The tubular wall portion 24 of the uppermost chamber 25 is secured to the tubular wall portion 19 by means of the nipples 26 and 27 in the same manner as the tubular wall portion 19 is secured to the tubular wall portion 16, and the nipple 26 serves to maintain constant communication between the uppermost chamber 25 and the intermediate chamber 20.

The nipple 23 is internally threaded to receive the threads on the pipe or conduit 28 which is open at both ends thereof and extends from near the top of the chamber 17 to a point a slight distance above the axis of the chamber 25. Said chamber 25 is provided with end walls 29 which are fixed to the tubular member 24 in liquid-tight relation to complete said chamber. From the upper portion of the tubular wall 24, a baffle 30 extends downwardly so that the bottom edge of said baffle is below the outlet end of the conduit 28 and is located between said upper outlet end of said conduit and the dry steam outlet connection 31 provided at substantially the middle of the length of the uppermost chamber 25. From the outlet connection, dry steam conduits 32 and 33 may extend to a plurality of pressing irons, the connection from the outlet pipe 31 to the conduits 32 and 33 being provided with a manually operated valve 34 to control the flow of steam out of the generator.

A large nipple or sleeve is fixed in an opening of the one end wall 18 of the bottom chamber 17, the same being threaded to receive the threads 36 on the heating device 37, said heating device thus being mounted on the one end wall 18 and extending longitudinally of the steam generating chamber 17 to adjacent the other end thereof. Referring to Fig. 3, it will be noted that a plu-

rality of the heating elements 37 is shown as being provided on the member 36 and said heater elements are made in such a manner that the heat produced thereby becomes more intense toward the free ends 38 of said members, the portions of said members 37 having the greatest heating capacity being located in substantially vertical alignment with the inlet end of the conduit 28, the steam generated thus passing directly into the inlet end of the conduit 28 and through the same into the receiving chamber 25.

The means for controlling the liquid level of water in the water receiving chamber 20 is illustrated as being a well known liquid level control unit 39, that illustrated being what is known as a McDonnell No. 47-2 Feeder-Cut-off-Combination manufactured by McDonnell & Miller, in which a float 40 controls the operation of a switch 41 which controls the position of a solenoid valve 42 which is in the liquid supply line, the inlet 43 from the water supply leading to the valve seat, and the water supply conduit 44 extends from said valve seat into the chamber 20, a nipple 45 being provided, fixed liquid-tight in the one end wall 21 of said chamber, to which said conduit 44 is secured in liquid-tight relation, the opening into the chamber 20 being below the normal liquid level 46, maintained therein by the regulator 39. In order that the float properly controls the liquid level through the mechanism of the control member 39, the pipe 47, extending from the T 13 to the drain valve 48, and the pipe 49 extending from the said valve into the regulator 39, is provided. The valve 48 is ordinarily closed to the drain pipe 50, but maintains communication between the pipes 47 and 49. Thus the water level in the float chamber 51 will be maintained at the same height as the water level 46 in the chamber 20 when the regulator is functioning. The water level regulator of the type referred to is also provided preferably with a connection from the steam collecting chamber, a nipple 52 being fixed liquid-tight in one of the end walls 29 of the chamber 25 to which a pipe 53 is connected screwthreadedly which leads to the upper portion of the float chamber, as will be obvious from Fig. 2 of the drawings. The conduit 44 is connected with the outlet opening 54 in the regulator 39.

The top steam collecting chamber 25, which constitutes substantially a steam dome for the generator, is also provided with a safety valve 55 which is mounted on the screwthreaded nipple 56 that is fixed liquid-tight in the tubular wall 24, and with a cuplike member 57 which is connected with the valve 58 leading to the nipple 59 that is mounted in liquid-tight fixed relation to the tubular wall 24 and extends through the same so that boiler compound can be supplied to the steam generator to remove scale from the tubular members that form the same.

The opposite end wall 29 to that having the pipe 53 extending therefrom is provided with an opening in which is mounted in liquid-tight relation a connection 60 leading to a pressure-operated switch 61 of the type that will open or close the circuit leading to the electric heater members 37 when the pressure falls below or reaches the desired maximum, respectively. A switch of the type suitable for this purpose is manufactured by the Detroit Lubricator Company and is known as their Type 25, Model NB-1 Control. A suitable electrical conduit 62 extends from the switch so as to connect the same in series with at least one of the line conductors

extending through the electrical conduit 63 to the terminal box 64 provided on the member 36 in a manner so as to control the supply of electrical energy to the electric heating members in accordance with the position of the contacts in the switch 61 so that whenever the pressure in the chamber 25 is below the desired pressure to be maintained, the switch 61 will close the circuit to the electric heater members, and as soon as the pressure of the steam in the chamber 25 reaches the desired maximum, the circuit to both of said heater members will be open so as to deenergize the same. The maximum pressure at which the switch opens is preferably set so that the switch will deenergize the electric heater elements 37 when the pressure in the chamber 25 reaches a predetermined value below the water pressure in the supply line 43.

Preferably, the liquid-tight connection, between the nipples 15, 22, 23, 26, 27, 31, 35, 45, 52, 56, 59 and 60, and the walls in which the same are mounted, is obtained by welding said nipples in the openings provided therefor in said walls, the nipples 22, 23, 26 and 27 thus rigidly securing the tubular members 16, 19 and 24 to each other. The end walls 18, 21 and 29 are also preferably welded to the tubular members liquid-tight.

In operation, the steam generator being filled with water to the predetermined level 46, and the operation of the device being started, the heating elements 37 will be energized until the pressure of the steam generated in the chamber 25 reaches the predetermined maximum at which the switch 61 deenergizes said elements. While the elements are being energized, steam will be generated in the chamber 17, and more rapidly near the ends 38 of the elements 37 and will pass upwardly through the conduit 28. Some entrained liquid may be in the steam passing through the conduit 28, and the baffle 30 prevents the passing of said liquid into the dry steam outlet connection 31, the liquid dropping to the bottom of the tubular wall 24, and this condenses, as it collects, then passing through the nipple 26 into the intermediate water chamber 20. Communication is continuously maintained between the chambers 20 and 17 so that the water in the chamber 17 will be replenished from the chamber 20 as the steam is generated, and the liquid level control 39 will supply water through the pipe 44 to the chamber 20 immediately upon reduction of the level therein to restore the water to the predetermined level 46 which is substantially that indicated in the drawing. Due to the provision of the controlling means for the pressure and the water level, and the means for generating the steam and collecting the same, dry steam at substantially constant pressure and constant dryness will be supplied to the pressing apparatus connected with the generator through the dry steam outlet connection 31.

When for any reason it is desired to drain the system of water, this can readily be done by means of the valve 48, as both the water level control 39 and the steam generator can be drained through the common drain connection 50 through the valve 48. Suitable connections 65 and 66 are provided for mounting a gauge-glass 67, the same being connected with threaded nipples 68 and 69 which are preferably welded in openings in the tubular walls 16 and 24 in the manner shown in Fig. 3. The entire heat gen-

erator is preferably surrounded by heat insulating material 70, as shown in Fig. 3.

Having thus described my invention, what I claim as new and desire to secure by Letters Patent is:

1. A steam generator comprising stacked tubes having end walls to provide a closed chamber in each thereof, nipples near the ends of said tubes connecting the adjacent ones thereof, the nipples near one end of said tubes establishing communication between adjacent chambers, an open ended conduit secured in the nipple connecting the bottom tube with the next adjacent tube and extending through said next adjacent tube and into the top tube a substantial distance, said conduit establishing communication between the bottom and top chambers, an outlet connection at the top of said top tube spaced from said conduit, a baffle between said outlet and the upper end of said conduit, and heating means in said bottom tube.

2. A steam generator comprising stacked tubes having end walls to provide a closed chamber in each thereof, a support for said stacked tubes comprising a nipple secured in the tubular wall of the bottom tube, a drain connection leading from said nipple, nipples near the ends of said tubes connecting the adjacent ones thereof, the nipples near one end of said tubes establishing communication between adjacent chambers, an open ended conduit secured in the nipple connecting the bottom tube with the next adjacent tube and extending through said next adjacent tube and into the top tube a substantial distance, a water inlet leading through an end wall of said next adjacent tube, said conduit establishing communication between the bottom and top chambers, an outlet connection at the top of said top tube spaced from said conduit, a baffle between said outlet and the upper end of said conduit, and heating means in said bottom tube.

3. A steam generator comprising stacked tubes having end walls to provide a closed chamber in each thereof, nipples near the ends of said tubes connecting the adjacent ones thereof, the nipples near one end of said tubes establishing communication between adjacent chambers, an open ended conduit secured in the nipple connecting the bottom tube with the next adjacent tube and extending through said next adjacent tube and into the top tube a substantial distance, said conduit establishing communication between the bottom and top chambers, an outlet connection at the top of said top tube spaced from said conduit, a baffle between said outlet and the upper end of said conduit, and heating means in said bottom tube extending longitudinally thereof and being constructed to have its greatest heating effect below the inlet end of said conduit.

HARRY PETER COOPER.
